UNITED STATES PATENT OFFICE.

IRA E. STAMETS, OF LOS ANGELES, CALIFORNIA.

COMBINATION DESK PAD.

1,412,318.

Specification of Letters Patent. Patented Apr. 11, 1922.

Application filed January 10, 1921. Serial No. 436,112.

To all whom it may concern:

Be it known that I, IRA E. STAMETS, a citizen of the United States, residing at Los Angeles, in the county of Los Angeles and State of California, have invented new and useful Improvements in Combination Desk Pads, of which the following is a specification.

This invention relates to combination desk pad, and particularly to a desk pad which has a fourfold purpose. It has for an object the provision of a desk pad which will be superior in point of relative simplicity and inexpensiveness, taken in conjunction with utility, durability and general efficiency and serviceability. In practicing the invention I provide a desk calendar which includes a daily journal section, a telephone index and a yearly calendar, as well as a daily desk calendar, all of which are suitably joined together and bound at one end to a cover.

With the above and other objects in view, the invention consists in the novel and useful provision, formation, construction, combination, association, inter-relation of parts, members and features, all as disclosed in the accompanying drawing, described in the following statement and finally pointed out in claims.

In the drawing:

Figure 1 is a perspective view of an improved desk pad;

Figure 2 shows one of the combination journal sheets detached from the pad shown in Figure 1; and

Figure 3 is a plan view of a telephone index member embodied in said pad.

Corresponding parts in all the figures are designated by the same reference characters.

Referring with particularity to the drawing, A designates a cover of the pad, B a phone call index, and C one of the important journal or diary sheets.

The cover A comprises a flap member a and a base member b. The cover may be made of any suitable material such as cardboard, etc., as well as made in any desired shape. The flap portion a and the base portion b are folded to turn over at the point marked 1. Within the flap portion a and the base portion b of the cover A is secured at the portion marked 1 by stitches 2 or other suitable means, a pack or series of

printed sheets B and C. The sheets B are indexed as at 3, each sheet having certain indications thereon so that the particular name upon a sheet may be readily located. One of the sheets as 4 has printed thereon "Phone calls," as shown at 5. One side of each sheet B has a space as 6 wherein a name may be written, and also a space as 7 for a telephone number, there being a ruling 8 separating the name and number. Obviously any number of sheets B may be included under the sheet 4, it being intended that each sheet has some indication as shown at 3 upon the same. Beneath the sheets B are located a pad or pack of the sheets C. Each of the sheets C is ruled as at 9 so that a person may jot down any memoranda upon the same. It will be noted that each sheet has thereon an important journal or diary for future reference form c, and a general journal or diary entry section d, there being a line of scoring 10 such as perforations, between the form c and the form d, whereby the form d may be separated from the form c. The form c really forms a stub portion of the pad and is permanently retained by said pad within the cover of same. The form c has printed just above the scoring 10 the words "Important journal notes above" followed by the day of the month. The form d at the bottom thereof as at 11 has on one side as 12 a complete last month's calendar, and at the opposite side of the sheet as 13 a complete next month's calendar. Between the said calendars 12 and 13 as at 14, 90 is located a daily calendar. Above said daily calendar as at 15 are printed the words "Yearly calendar on the last sheet." It will thus be seen that a pad of this type combines, and has been pointed out, four important elements. First, a daily desk calendar shown at 14, a combination journal as shown at c and d, a telephone index as shown at B, and a yearly calendar, not shown, but intended to be printed upon the base b of the cover A.

The flap a does not completely cover the sheet C, but is intended only to cover the portion of the sheet C marked c, as well as the sheets comprising the telephone index B. Obviously each person using the desk pad will find certain ways and means of using the same to enhance his best interests. However, it is intended that the sections d contain notations or other items that may 110

arise during the day, and that the sections *c* should contain notations or other items of special importance for future reference. It is to be noted that the date on the journal section *c* corresponds with that of the daily calendar 14 on the portion *d*. The journal section *c* which is permanently bound as at 1, makes a yearly diary which is always available and may be filed intact. In practicing the invention the pad is so formed that each sheet will open flat. In other words, instead of gluing the ends of the pads *B* and *C* each sheet is machine-sewed, and the portion 1 is made like a book cover. This book binding for a pad of this description is an important feature, in that practically no pad now on the market includes this feature. The flap *a* may have printed upon its surface as at 15 numerals representative of the year, as 16, or in place of using the numerals as at 16 the name of a firm might be printed thereon, especially if some firm desired to give its clients or customers pads as a Christmas gift.

It is obvious that many changes and modifications and variations may be made in practicing the foregoing invention, as described, all without departing from the true spirit of the invention.

Having thus disclosed my invention, I claim and desire to secure by Letters Patent:

1. In a device of the character described, the combination with a cover, of a series of leaves joined therewith, each leaf having lines placed thereon to form spaces for notations, an important journal or diary for future reference form, and a general journal or diary entry section; said first named form being near the top of the leaves and having a line of scoring between itself and the second named form whereby the latter may be detached from said first named form, with the portion of the leaves provided with the first named form permanently maintained to and beneath the cover.
2. In a device of the character described, the combination with a cover, of a series of leaves joined therewith, each leaf having lines placed thereon to form spaces for notations, an important journal or diary for future reference form, and a general journal or diary entry section; said first named form being near the top of the leaves and having a line of scoring between itself and the second named form whereby the latter may be detached from said first named form, with the portion of the leaves provided with the first named form permanently maintained to and beneath the cover; said second named form having a last month, next month, and a daily calendar thereon, and the first

named form likewise having a daily calendar thereon.

3. In a device of the character described, the combination, with a cover, of a series of leaves joined therewith, each leaf having lines placed thereon to form spaces for notations, certain of the leaves being indexed for telephone numbers and other of the leaves having an important journal or diary for future reference form, and a general journal or diary entry section; said important journal or diary form being near the top of the leaves and having a line of scoring between itself and the general journal section, whereby the latter section may be detached from the important journal form.

4. In a device of the character described, the combination, with a cover, of a series of leaves joined therewith, each leaf having lines placed thereon to form spaces for notations, certain of the leaves being indexed for telephone numbers and other of the leaves having an important journal or diary for future reference form, and a general journal or diary entry section; said important journal or diary form being near the top of the leaves and having a line of scoring between itself and the general journal section, whereby the latter section may be detached from the important journal form; said general journal section having a last month, next month, and a daily calendar thereon, and the important journal form likewise having a daily calendar thereon.

5. In a device of the character described, the combination, with a cover, of a series of leaves joined therewith, each leaf having lines placed thereon to form spaces for notations, certain of the leaves being indexed for telephone numbers and other of the leaves having an important journal or diary for future reference form, and a general journal or diary entry section; said important journal or diary form being near the top of the leaves and having a line of scoring between itself and the general journal section, whereby the latter section may be detached from the important journal form; said cover including a base and top flap; said flap, telephone leaves and important journal form leaves being of like size, and the said leaves being bound at one end within said cover in such a manner that the leaves open flat.

In testimony whereof, I have signed my name to this specification in the presence of two subscribing witnesses.

IRA E. STAMETS.
